ALICE URILLA DAVIS, OF EL PASO, TEXAS.

PAPER-GUIDE.

1,040,901.

Specification of Letters Patent.

Patented Oct. 8, 1912.

Application filed December 12, 1911. Serial No. 665,222.

To all whom it may concern:

Be it known that I, ALICE U. DAVIS, a citizen of the United States, and a resident of El Paso, in the county of El Paso and State 5 of Texas, have invented a new and improved Paper-Guide, of which the following is a full, clear, and exact description.

Among the principal objects for which the present invention is designed are: to provide 10 means for guiding the paper and carbon inserts to and from a typewriting machine cylinder, to prevent the disarrangement of the sheets of paper or carbon inserts carried thereby, after delivering from the 15 platen; and to provide means for holding the paper, which are light, simple and durable in construction.

Reference is to be had to the accompanying drawings forming a part of this specification, in which similar characters of reference indicate corresponding parts in all the views, and in which—

Figure 1 is a side view of a fragment of the frame of a typewriting machine, showing in conjunction therewith means for guiding the paper on delivery from the platen, said means being constructed and arranged in accordance with the present invention; Fig. 2 is a detail view, on an enlarged scale, showing a top view of the paper-support and guide constructed and arranged in accordance with the present invention; Fig. 3 is an edge view of the guide; Fig. 4 is a detail view, showing in its separate relation 30 the back bar to the guide; Fig. 5 is a detail view, on an enlarged scale, showing the mounting of the back bar and bracket arms; Fig. 6 is a detail view in section, taken on the line 6—6 in Fig. 5; Fig. 7 is a detail view 35 in section, taken on the line 7—7 in Fig. 3; and Fig. 8 is a detail view in section, taken on the line 8—8 in Fig. 2.

An advantage in the use of this particular device is that the limp carbons are prevented 40 from falling or curling between the leaves of the paper before the paper and carbons enter the paper-feeding device, thus preventing blank spaces on the carbon copies. It is for this purpose that the attachment of the 45 device is made to the sides of the paper table 15, which paper table is usually furnished in typewriting machines. The support and guide herein shown is formed as a rectangular H-frame, the parallel members of which 50 are formed by bracket-bars 16, 16. The bars 16, 16, at the outer ends, are provided with

elongated slots 17. Each slot 17 holds 60 snugly the square shank 18 of each screw 19. The shank 18 is rectangular, the opposite sides of the said shank being each adapted to fit one of the slots 20, 20 formed in the rest-bar 21, (seen best in Fig. 4 of drawings). The length of the shank 18 is slightly less than the combined thicknesses of one 65 of the bars 16 and the rest-bar 21. This discrepancy in length of the shank permits the clamping of the bars 16 and 21 between the head 22 formed at the outer side of the shank 18 and the flange of a milled nut 23. The milled nuts 23, 23 are each tapped to 70 register with the threads of the screws 19.

The lower ends of the bars 16 are each provided with an undeturned section 24, and an overturned section 25. The sections 24 and 25 are separated, (as seen best at 75 Fig. 8 of drawings), to straddle the lateral edges of the paper table 15. The section 25 is tapped to provide a threaded perforation with which the threads of a screw 26 register. When the screws 26, 26 are upset hard 80 against the table 15, the bars 16 are held rigidly in adjusted position.

At the outer ends of the rest-bar 21 are provided tapped and threaded perforations 85 27, 27. The perforations 27 are provided to receive the threaded ends 28 of screws 29. The screws 29 are provided with milled heads, as seen best at Fig. 7 of drawings. Intermediate the head of the screw 29 and the threaded section 28 is formed a groove 90 30. The groove 30 is provided to receive in operative position a holding bar 31 (seen best in Fig. 2 of drawings). At each end of the holding bar 31 is formed an eyelet 32. The enlarged portion of the eyelet 32 is 95 formed to a dimension capable of passing the screw 29 and the body of the shank wherein is formed the groove 30. The narrowed portion of the eyelet 32 is formed to a dimension to snugly fit the shank of the 100 screw 29 within the groove 30. By means of this arrangement, the holding bar 31 is quickly adjusted in position to override the paper as the same is delivered from the platen of the typewriting machine. The adjustment is effected by superposing the enlarged portions of the eyelets 32 over the heads of the screws 29, until the same register with the grooves 30, when, the bar 31 being moved toward the narrowed sections 105 of the eyelets, the said narrowed sections of the eyelets straddle the reduced shank with

in the groove 30. Screws 29 are threaded to allow them to be screwed in and out, thus making the space between the back bar, shown in Fig. 3, and the holding bar, adjust 5 justable to form the space necessary for any number of sheets of paper and carbon.

To stiffen the bar 31, I have provided a standing flange 33. The bar 31 is also provided with a finger-hold or handle 34, by 10 which the said bar is adjusted.

With a device constructed and arranged as shown in the accompanying drawings, and after the same has been installed in position on the table 15 by clamping the said table between the sections 24 and end of the screws 26, the rest-bar 21 is adjusted to suit the length and character of the paper being used in the typewriting machine. In making this adjustment, the method pursued by 20 the operator is to loosen the nuts 23. This releases the clamping engagement of the bars 16 and 21; the bar 21 is then moved lengthwise of the slots 17 in the bar 16. In all positions of the bars 16 and 21, the shanks 18 maintain the perpendicular relation of the said bars. When the adjustments between the bars 16 and 21 have been properly attained, the nuts 23 are set up against the exposed surface of the bars 16, to clamp 25 said bars 16 and 21 in fixed relation. If preferred, the holding bar 31 may be removed while making the adjustment above described. When the paper A is placed in printing position upon the platen B of the 30 machine, the upper edge thereof is bent down to rest upon the bar 21. While the

paper is in this position, the holding bar 31 is adjusted upon the screws 29, and shifted to lock within the grooves 30 thereof. Thereafter, the paper is guided as it is delivered from the platen B, and is held in such position that the carbon inserts do not fold over or become otherwise disadjusted between the sheets of paper being imprinted.

Having thus described my invention, I 45 claim as new and desire to secure by Letters Patent:—

1. A paper guide, comprising a plurality of supporting arms; a rest-bar adjustably mounted on said supporting arms; and a holding member detachably mounted upon said rest-bar to form a guiding slot for the paper as delivered to and from the platen of a typewriting machine.

2. A paper guide, comprising a plurality of longitudinally slotted supporting bars; a cross-bar having adjacent the ends thereof longitudinally-disposed slots; a rectangular sliding member disposed in said slots to maintain said bars in perpendicular relation; means for clamping said bars in fixed relation; a holding bar disposed above said rest-bar; and suitable button and eyelet connections between said rest-bar and said holding bar.

In testimony whereof I have signed my name to this specification in the presence of two subscribing witnesses.

ALICE URILLA DAVIS.
